UNITED STATES PATENT OFFICE.

JAMES C. REID, OF LINCOLN, NEBRASKA.

BUFFET TABLE.

Application filed June 29, 1927. Serial No. 202,328.

This invention relates to tables adapted to be extended from an article of furniture.

An object of the invention comprehends leaves for the table adapted to provide a top 5 for the furniture.

Another object of the invention contemplates leg members for the table.

A further object consists of means adapted to permit access to the interior of the 10 furniture when the table is called into use.

More specifically stated the table legs are adapted for connection with the furniture legs to resemble unitary leg structures.

With the above and other objects in view, 15 the invention further consists of the following novel features and details of construction to be hereinafter more fully described, illustrated in the accompanying drawings, and pointed out in the appended claims.

20 In the drawings:

Figure 1 is a perspective view of an article of furniture with the invention applied.

Figure 2 is a similar view illustrating the extended position of the table.

25 Figure 3 is a transverse sectional view taken through the article of furniture with the invention folded thereon.

Figure 4 is a similar view with the table extended.

30 Figure 5 is a detail sectional view taken through one corner of the furniture and illustrative of the connection between the legs of the furniture and table.

Figures 6 and 7 are detail views of the 35 hinged connections for the table leaves.

Referring to the drawings in detail, wherein like characters of reference denote corresponding parts, the reference character 10 indicates an article of furniture which may 40 be in the form of a serving table, buffet or the like.

It has been extremely difficult for furniture dealers to supply the needs of occupants of small apartments due to fact that the customary size of tables for dining room suites take up too much of the confined area. Sometimes serving tables are used and at other times gate leg tables employed. The apartment when furnished in 45 such manner does not appear complete due to the diminutive sizes of the articles of furniture.

It is my intention, in this respect, to combine a table with the conventional form and 50 size of buffet in order that the buffet may be

utilized to accommodate the table and occupy only its respective area.

In carrying out the invention I provide leaf members 11 and 12 hingedly connected as indicated at 13. The side edge of the leaf 11 adjacent the forward side of the top for the buffet 10 is hingedly connected therewith as indicated at 14. The adjacent corners of buffet top and leaf 11 are cut off, the purpose of which will be 60 readily apparent. The legs upon the forward corners of the buffet are cut in half longitudinally thereof and the severed halves being carried adjacent the outer corners of the leaves 12 and upon the undersides 65 thereof. The leaf 12 is slightly wider than the leaf 11 to provide an overhanging edge upon the front of the article of furniture and to furthermore accommodate brace members 14' upon the undersides thereof 70 operatively connected with the half legs carried upon the underside of the aforementioned leaf to strengthen the same.

When the table is extended for use it may be necessary to have access to the silver 80 drawer generally located in the upper portion of the buffet and to provide the utmost of convenience. A swingably mounted panel 15 is provided within the top of the buffet immediately over the aforementioned 85 drawer. As illustrated in Figures 1, 2 and 4 the half legs carried by the leaf 12 are shorter than the remaining portions of the legs carried by the buffet. This was necessary due to the fact that the thickness of 90 the respective leaves when folded one upon the other would elevate the half legs an appreciable extent approximate to that of the height of the shoulder portions 16 carried upon the remaining leg portions of the 95 buffet and upon which the extremities of the half legs for the leaves 12 are supported.

Access may be had to the sides of the buffet through doors 17. The sides of the buffet may be employed for dishes or cupboard 100 spaces.

The corners removed from the buffet top and leaf 11 permit the half legs to be snugly fitted against the remaining leg portions carried by the buffet.

Hinge members of suitable types and designs may be effectively employed to cause close fitting edges for the leaves and to prevent the table from dipping or sagging in the middle when called into use.

The table when extended will permit chairs to be set up at the ends of the leaves and upon the front of the leaf 12 to conveniently seat four or more diners.

5 The invention is susceptible of various changes in its form, proportions and minor details of construction, and the right is herein reserved to make such changes as properly fall within the scope of the appended claims.

Having described the invention, what is claimed is:

1. In a device of the character described comprising an article of furniture having a plurality of drawers, table leaves hingedly connected with the article, legs carried upon the forward portions of the article, said legs having portions removed, said removed portions being carried upon one of the leaves 15 to support the table when extended for use, brace members carried by one of the leaves and adapted for connection with said removed portions, and shoulder portions carried upon the legs for the article of furniture 20 adapted to support the extremities of the removed portions carried by the table leaf.

2. In a device of the character described comprising an article of furniture having a plurality of drawers, table leaves hingedly 25 connected with the article, legs carried upon the forward portions of the article, said legs having portions removed, said removed por-

tions being carried upon one of the leaves to support the table when extended for use, brace members carried by one of the leaves 35 adapted for connection with said portions, shoulder portions carried upon the legs for the article of furniture adapted to support the extremities of the removed portions carried by the table leaf in order that the original design of the legs may be preserved, and means carried by the article of furniture whereby access may be had to the drawers when the table is extended for use.

3. In a device of the character described 45 comprising an article of furniture provided with leg members, said members having portions removed, and a table carried by the removed portions and adapted to be supported thereby when extended for use. 50

4. In a device of the character described comprising an article of furniture having a plurality of drawers, a table supported upon the article of furniture, legs for the article of furniture, said legs having portions removed, the removed portions being carried by the table to support the latter when extended from the article of furniture, and means carried by the table and removed portions adapted to permit access to the 55 drawers when the table is extended for use. 60

In testimony whereof I affix my signature.

JAMES C. REID.
